SMOKER'S ASH RECEPTACLE

Douglas Stuart Harwood, Hillside,
Birkdale, EnglandApplication December 20, 1950, Serial No. 201,725
In Great Britain February 9, 1950

4 Claims. (Cl. 220—20.5)

1

This invention relates to smokers' ash receptacles, and has for its object to provide a receptacle of simple and therefore inexpensive, construction, whereby the extinguishing and disposal of smouldering tobacco and tobacco ash is facilitated.

A smoker's ash receptacle, according to my invention, comprises a container having an opening formed in its upper portion, and a downwardly displaceable and tilttable (in any direction) member of domed, conical, or other suitable downwardly sloping configuration which normally closes the opening, and said closure member being supported within the container by spring means whereby a substantially airtight connection is maintained between the closure and the rim of said opening.

In a preferred construction of my receptacle, its rim is provided with an inwardly and downwardly directed lip or flange the under surface or edge whereof is adapted to form a seating for said closure member; and a number of radial grooves or channels, or radiused supporting plates, for the reception of cigarettes, or the like, are provided on said rim which is of a depth enabling it, in conjunction with the abutting closure member, to be used as a conventional ash-tray.

Said closure member may be formed or provided with a knob, or the like, whereby its displacement against the resistance of its spring supporting means is facilitated to permit ash and burning or smouldering tobacco, matches or the like, deposited on said closure, to be precipitated from its downwardly curved or sloping sides into the container. When the closure is permitted to reseat itself against the underside of the container's rim, ingress of air to the container is prevented, or substantially so, and the burning or smouldering tobacco is quickly extinguished without necessity for it to be handled by a smoker—with consequential soiling of the hands or fingers—and without any unpleasant and prolonged smouldering of the tobacco.

I will further describe my invention with the aid of the accompanying sheet of explanatory drawings which illustrate, by way of example only, and not of limitation, two modes of embodiment.

In said drawings:

Fig. 1 is a side elevation of a smoker's ash receptacle.

Fig. 2 is a plan view, and

Fig. 3 is a transverse section taken as on line A—A Fig. 2.

Fig. 4 is a view, as in Fig. 3, of a modified ash receptacle.

Referring now to said drawings, *a*, *b*, denote,

2

respectively, upper and lower separable container components, upper component *a* having a peripheral rim *c* formed with a number of spaced-apart radial grooves *d* for the reception of cigarettes, or the like. The edge *e* of an inturned lip or flange *e* of rim *c* is adapted to form a seating for a closure member *f* of conical configuration, and which is supported and normally held in abutment with edge *e* by means of a rod *g* slidably located in a sleeve *h* formed integrally with container base *b*. Said rod *g* has screwed onto its upper extremity a hemispherical head *j* which engages with a correspondingly configurated recess *k* formed in the underside of closure member *f*, and is spring influenced by means of a helical compression spring *l*. The lower end of rod *g* is flanged as at *m*, said flange cooperating with a shoulder *n* formed internally of sleeve *h* to prevent dissociation of said rod from the container base *b*.

Upper and lower components *a*, *b* of said container may be connected by means of cooperating screwthreads, as *a*¹, *b*¹, to permit separation of components *a*, *b* for emptying and/or cleaning.

A knob *o*—with grooves *o*¹ in radial alignment with grooves *d* of rim *c*—is provided on closure *f* to facilitate the depression of same by hand when discharge of ash, matches, and the like, from said closure into the container is desired.

In use, tobacco ash, cigarette ends, matches, and the like, may be deposited on closure *f* as in a conventional ash tray, and when said closure is depressed by hand all the deposited matter is precipitated within the container. When—after actuation—closure *f* is permitted, under the influence of spring *l*, to reseat itself against edge *e* of rim *e*, ingress of air to the container is wholly or largely prevented and consequently any burning or smouldering tobacco is quickly and automatically extinguished, without unpleasant and prolonged smouldering. To empty the contents of the container it is only necessary to dissociate the container components *a*, and *b*, when ash and the like may be emptied therefrom for disposal as desired. It is to be noted that, owing to the—in effect—universal form of connection between closure *f* and the head *j* of rod *g*, said closure may be depressed and tilted in any direction to facilitate the precipitation of ash and cigarette-ends into the container; and further, said universal connection ensures that an airtight seating of closure *f* is automatically made when pressure is removed from knob *o*. Flanged rim *e* may, of course, be formed integrally with the container, or be adapted for fitment thereto as by appropriate screw threading of the cooperating parts, and the spring supporting means

may be associated with said flanged rim, or the container sides, as desired.

If desired the closure f may be provided on its underside with a second or subsidiary container f^1 (Fig. 4) closed from the main container but communicating with the upper curved or sloping surface of said closure by means of a series of perforations f^2 formed therein. Said subsidiary container f^1 is adapted to be secured to and readily released from said closure by co-operating screw threads f^3 formed on an annular ridge or flange f^4 of said closure and the periphery of said container f^1 . In order that the universal movement of said closure is in no way restricted a central opening is formed in said container and a conical sleeve is secured to the latter, the upper edge f^5 whereof, is, when the container is secured to said closure, adapted to seat, in more or less air-tight manner, against the underside of said closure. Container f^1 is intended to receive ash—via the provided perforations f^2 —deposited on the closure but not the smouldering tobacco remains which are precipitated within the main container a, b , to be extinguished as hereinbefore described.

In an alternative form of embodiment said closure may comprise a more or less flat plate with a chamfered periphery adapted to engage the flange e of the container, and, removably supported by said plate, is a perforate domed or equivalent member. The curved or sloping sides of the dome effect disposition of tobacco remains within the container on depressing said closure, and fine ash falls through the perforations of the dome onto the plate below. Said domed member may be spaced from its supporting plate, or have a plurality of apertures formed around its periphery, to facilitate the removal of ash therefrom.

Ash receptacles constructed in accordance with my invention may with advantage be readily adapted for fitment and use in cinemas, theatres, omnibuses, trains, and like places, and may be of any required configuration and of any suitable material without departing from the scope of the invention.

What I claim as my invention and desire to secure by Letters Patent is:

1. A smoker's ash receptacle comprising a container having detachable upper and lower sections being connected together by interengaging screw threaded portions, said upper section having an opening provided in the top thereof, a conical member positioned within said container for closing said opening, a sleeve formed integrally through the base of said container lower section and having a shoulder provided in the bore thereof, a rod slidably mounted through said sleeve and having a threaded upper end portion, said rod having a flange provided at the lower end thereof for engaging said sleeve shoulder for limiting the upward movement of said rod, a hemi-spherical head having a threaded recess in threaded engagement with said rod threaded end portion, a helical spring positioned around said rod and between said head and said sleeve, said closure member having a recess provided in the underside thereof for slidably receiving said head therein whereby said closure is downwardly displaceable by hand against the influence of said spring and tiltable in any direction on said rod.

2. A smoker's ash receptacle comprising a cup shaped container having a threaded inner edge portion, an inverted cup shaped closure having a threaded outer edge portion in threaded en-

gagement with said container, said closure having an opening provided in the top thereof, said closure further having an annular flange formed therewith extending downwardly from the edge thereof defining said opening, a conical member positioned within said container for bearing against said flange and extending thereacross, a sleeve formed integrally with and extending upwardly from the inner bottom of said container, said container having a recess provided through the bottom thereof into said sleeve and communicating with and being of greater width than the bore of said sleeve, a rod slidably mounted through said sleeve bore and container recess, said rod having a flange provided on the lower end thereof for sliding in said container recess, a hemi-spherical head detachably mounted on the upper end of said rod, a helical spring positioned around said rod between said head and the top of said sleeve, and said conical member being loosely and detachably mounted on said head for tilting in any direction thereon and normally being held in airtight abutment against the lower edge of said flange.

25 3. A smoker's ash receptacle comprising, a container having an opening formed in the upper portion, a member with downwardly sloping sides for closing said opening, a subsidiary container detachably secured to the underside of said closure member and closed from the main container but communicating with the upper surface of said closure by a number of perforations formed in the latter, a spring influenced support for said closure member, and a connection between said spring support and closure member whereby the latter is downwardly displaceable and tiltable in any direction.

4. A smoker's ash receptacle comprising, a container formed in two parts and connected by co-operating screw threaded portions, an opening in the upper portion of said container, provided with a downwardly directed flange, a member with downwardly sloping sides for closing said opening, a subsidiary container detachably secured to the underside of said closure member and closed from the main container but communicating with the upper surface of said closure member by a number of perforations formed in the latter, a rod slidably located in a sleeve formed in the base of said container and having a hemi-spherical head, a helical spring disposed around said rod between said head and sleeve, a recess formed in the underside of said closure wherewith the head of said rod engages and whereby the closure is normally held in substantially air-tight abutment with the lower edge of the container's opening.
